UNITED STATES PATENT OFFICE

92,873

DESIGN FOR A CAN PUNCTURING DEVICE

Frank Alleva, Yonkers, N. Y.

Application April 5, 1934, Serial No. 51,317

Term of patent 7 years

To all whom it may concern:

Be it known that I, FRANK ALLEVA, a citizen of the United States, residing at Yonkers, in the county of Westchester and State of New York, have invented a new, original, and ornamental Design for a Can Puncturing Device, of which the following is a specification, reference being had to the accompanying drawing, forming part thereof.

Figure 1 is a view in side elevation of a can puncturing device, showing my new design.

Figure 2 is a view in top plan thereof.

Figure 3 is a bottom plan view.

I claim:

The ornamental design for a can puncturing device as shown.

FRANK ALLEVA.
